Primary Examiner — Tamara L Hahn(74) *Attorney, Agent, or Firm* — Fitch, Even, Tabin & Flannery LLP(57) **CLAIM**

The ornamental design for a conveyor belt cleaner blade, as shown and described.

DESCRIPTION

FIG. 1 is a perspective view of a conveyor belt cleaner blade, showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is an end elevational view thereof; the opposite end being identical.
